UNITED STATES PATENT OFFICE.

ROSA MARGUERITTE PETERS, OF NEW YORK, N. Y.

HEAD AND SOCKET FASTENER.

Application filed October 11, 1922. Serial No. 593,878.

To all whom it may concern:

Be it known that I, ROSA M. PETERS, a citizen of the United States, and a resident of the city of New York, borough of Manhattan, in the county and State of New York, have invented new and useful Improvements in Head and Socket Fasteners, of which the following is a full, clear, and exact description.

10 This invention relates to head and socket fasteners.

In providing head and socket fasteners for clothing for stout people a great deal of difficulty is experienced in providing a fastener 15 which does not open when the clothing is subjected to strains. Fasteners that will not remain closed are objectionable.

The general object of this invention is the provision of a cheap, simple and efficient 20 head and socket fastener so constructed that when it is closed it will remain so until it is opened by the wearer.

This object is accomplished by providing a base plate having a head mounted thereon 25 carrying lugs and forming a mating plate having a socket shaped to receive the head and adapted to retain the head in position after it has been turned through an angle.

This and other objects of the invention 30 will be more clearly understood from the following detailed description and accompanying drawings.

Figure 1 is a top plan view of the base 35 plate;

Figure 2 is a bottom plan view of the mating plate provided in conjunction with the base plate;

Figure 3 is a vertical section through the head and socket fastener, showing it after 40 the plates have been forced together.

Referring to the above-mentioned drawings, the invention includes a base plate 10 provided with a plurality of openings 11. The openings 11 are provided so that the plate 10 may be sewed to the fabric. Integral with the base plate 10 and extending upward from its center is a hollow shank 12 carrying a head 13. Formed integral with the head 13 are two projections 14 and 15 on 45 opposite sides of the head 13.

A mating plate 16 having a rim 17 integral therewith carries a socket 18. Slots 20 extending at right angles to the height of the socket 18 are cut in its sides and the arms of a spring 19 located inside the rim 17 extend into these slots, serving as a means for locking the head 13 in position in the socket. This spring member for locking the head in the socket is provided in a great many fasteners and is not considered new. Two 55 notches 21 and 22 are also cut in the walls of the socket 18 and extend parallel to the height of the socket. The size of these notches is sufficient to allow the projections 14 and 15 on the head 13 to be moved 60 through them. The mating plate 16 is provided with a number of openings 23 so that it may be sewed to the fabric.

In attaching the base plate 10 and the mating plate 16 to the edges of fabrics for 70 connecting them together it would be necessary in order to make use of the locking means to mount the base plate so that a line drawn through the projections 14 and 15 would be at right angles to a line drawn 75 through the notches 21 and 22. When the plates are mounted in this manner, in order to connect them, one of the members must be turned through an angle of 90° by twisting the fabric to which it is connected. The 80 head 13 is then inserted into the socket 18. The fabric in regaining its normal position, will rotate the head 13 through an angle of 90° and the projections 14 and 15 engage the walls of the socket 18, locking the head 85 in position. Thus it will be seen that a fastener provided with locking means has been provided.

I would state in conclusion that while the illustrated example constitutes a practical 90 embodiment of my invention I do not limit myself strictly to the exact details herein illustrated since manifestly the same can be considerably varied without departing from the spirit of the invention as defined in the 95 appended claim.

Claim:

A head and socket fastener of the character described comprising a base plate having an upstanding shank, a head on said shank 100

having oppositely extending projections, a rim of the mating plate having arms mounted through the slots in the socket for locking the head in the socket when the head has been inserted therein and turned to bring the projections thereon substantially at right angles to the grooves in the sockets.

ROSA MARGUERITTE PETERS.
